UNITED STATES PATENT OFFICE

2,487,017

GARMENT BLOCKING AND DRYING DEVICE

Matthew Brandys, Chicago, Ill.

Application March 29, 1946, Serial No. 658,144

3 Claims. (Cl. 223—69)

1

The present invention relates to garment blocking and drying devices of the type having a pair of complementary sections, the side portions of which generally conform to the outline of the garment to be blocked or dried, and which sections are extensible on a horizontal plane for the purpose of making the device adaptable for use in connection with various sizes of garments.

The principal object of the present invention is to provide in a garment blocking and drying device of the character hereinabove indicated, the telescopic means wherein the horizontal wire members of the device may be slidably fitted for extending the device horizontally in order to make the same conform to various sizes of garments.

A still further object of the present invention is the provision in connection with the telescopic means aforesaid of suitable camming device, such as disclosed in my co-pending application filed February 7, 1946, Serial No. 646,015, for the purpose of rigidly locking horizontal portions of the blocking and drying device when the same are extended on horizontal plane to maintain two complementary sections of the device in their rigid, adjusted positions.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views:

Fig. 1 is a plan elevational view of the present device;

Fig. 2 is an enlarged side elevational view of the adjusting means for horizontal wire members of the device, with the cooperating camming device for maintaining the extended wire members in a rigid adjusted position;

Fig. 3 is a cross-sectional view through a horizontal wire member, showing the camming device in an edge elevation when in an operative position; and

Fig. 4 is an enlarged cross-sectional view on line 4—4 of Fig. 2.

Referring in detail to the present drawing there is shown therein a blocking and drying device, generally indicated by 10, and which embodies a pair of complementary sections 11, the upper ends of which are outwardly curving, generally conforming to the contour of a garment such as

2

sweater or the like, while the lower portions of which are straight and parallel.

The ends of one section 11 are bent substantially at right angles to the body of said section 11 for defining wire stubs 12. Intermediately of two ends of that last named section 11 wire stub 13 is soldered or otherwise rigidly affixed thereto. Said stubs 12 and 13 are in a mutual parallel relation, and in a transverse position with respect to their cooperating section 11. Inserted upon the free end of each stub 12 and 13 and there soldered, crimped or otherwise rigidly affixed, is an oblong tubular member 14.

Aligned with said stubs 12, and extending from the opposite section 11 are wire members 15, which are defined by bending horizontally the end portions of said last named section 11. Cooperating with stub 13 is wire member 16, soldered or otherwise rigidly affixed to the body portion of said last named section 11, and oppositely to stub 13. Wire members 15 and 16 are comparatively long and enter by their free ends tubular members 14 and when two sections 11 are shifted towards each other the ends of stubs 12 and 13 contact and bear against the free ends of wire members 15 and 16, respectively.

Integrally formed with the free ends of tubular members 14, and extending in a parallel relation from diametrically opposite points of the periphery thereof, is a pair of spaced leaves 17. Receivable within each pair of said leaves 17 is a pair of camming plates 18 having camming edges 19. Said camming plates 18 are formed out of a single blank, as disclosed in my said co-pending application, so that along one side edge thereof, said camming plates 18 are joined by a U-shaped edge portion 20 of the blank. Integrally formed with said camming plates 18 is handle 21.

Extended through said leaves 17 and camming plates 18 is rivet 22, providing a pivot upon which camming plates 18 and handle 21 may be angularly swung into an operative position shown in full lines in Fig. 2, or into an inoperative position indicated by dotted lines in Fig. 2. When the cam is in an operative position, edges 19 enter into the corners defined by the periphery of wires 15 or 16, and the adjacent face portions of leaves 17. By virtue of this operation said edges 19 enter into a strong frictional contact with said wires 15 and 16 and bear against them in a transverse direction for the purpose of clamping the same to the adjacent body portions of said tubular members 14 oppositely disposed to said leaves 17. This operation will lock said wires 15 and 16

in their adjusted position with relation to said tubular members 14.

From the hereinabove description it will be seen that when all cams are open, with plates 18 out of engagement with wire members 15 or 16, said wire members 15 and 16 may then be shifted within their tubular members 14 for shifting sections 11 away from each other to a number of adjusted positions as indicated by dotted lines in Fig. 1. When said sections 11 were shifted away from each other, and the same made to conform to the particular desired size of any given garment, then handles 21 of the cams are swung into vertical positions for engaging wire members 15 or 16 by cam plates 18 as aforesaid, for maintaining said wire members 15 or 16 in a rigid locked position with respect to their respective tubular members 14 and thereby maintain sections 11 in a rigid adjusted position.

While there is described herein a preferred embodiment of the present invention, it is nevertheless to be understood that minor changes may be made therein without departing from the spirit and scope of the invention as claimed.

What I claim as new is:

1. A garment blocking and drying device comprising a pair of complementary sections, each of said sections being of a contour substantially conforming to the garment when the same is placed upon said sections, a plurality of wire members extending substantially at right angles from the body portion of each section, said wire members in the two sections being in a longitudinal alignment, tubular members carried by wire members in one of said sections, the wire members in the other of said sections entering said tubular members for sliding movement therewith for adjusting the distance between said sections for substantially conforming the same to the width of the garment thereon, and locking means carried by said tubular members for engaging said last named wire members for maintaining the same in an adjusted position.

2. A garment blocking and drying device comprising a pair of complementary sections, a plurality of wire members extending substantially at right angles from the body portion of each sec-

tion, said wire members in the two sections being in a longitudinal alignment, tubular members carried by wire members in one of said sections, the wire members in the other of said sections entering said tubular members for sliding movement therewithin, a pair of leaves rigidly formed with and extending from each of said tubular members, and a cam mechanism pivoted within said leaves for selectively rigidly engaging said last named wire members for maintaining the same in an adjusted position.

3. A garment blocking and drying device comprising a pair of complementary sections, a plurality of wire members extending substantially at right angles from the body portion of each section, said wire members in the two sections being in a longitudinal alignment, tubular members carried by wire members in one of said sections, the wire members in the other of said sections entering said tubular members for sliding movement therewithin, a pair of leaves rigidly formed with and extending from each of said tubular members, and a cam mechanism pivoted within said leaves for selectively rigidly engaging said last named wire members for maintaining the same in an adjusted position, said cam mechanism including a pair of plates entering the corners defined by the peripheries of said last named wire members and said leaves for frictionally engaging said last named wire members for clamping the same to the body portions of said tubular members oppositely disposed to said leaves.
